UNITED STATES PATENT OFFICE.

WILLIAM ENGELSDORFF, OF CHICAGO, ILLINOIS.

IMPROVEMENT IN CORKSCREWS.

Specification forming part of Letters Patent No. 172,104, dated January 11, 1876; application filed June 3, 1875.

To all whom it may concern:

Be it known that I, WILLIAM ENGELSDORFF, of Chicago, in the county of Cook and State of Illinois, have invented an Improved Cork-Extractor, of which the following is a specification:

My invention has for its object to provide a device for easily extracting corks from bottles without damage to the corks, so that they will not be spoiled for subsequent use, as is the case when a corkscrew is used; and it consists in the peculiar construction and conformation of the implement, as will be more fully hereinafter set forth.

Figure 1 is a perspective view. Fig. 2 is a cross-section at *xx*.

In the drawing, *A* represents a tapered stock, of metal, having at its upper and larger end a T-handle, *B*, and terminating at the lower end in a lateral blade, *a*, having a convex lower edge, and curved to a segment of a circle, to conform to the walls of the neck of the bottle; it is bent slightly outward, so as to cause the point to slide in contact with the bottle when inserted and pushed down be-

tween it and the cork, so as not to catch against the latter. At the upper edge there is an upward-projecting spur, *b*, to catch and engage with the lower end of the cork, and retain it on the instrument after it is extracted, instead of allowing it to fall to the floor, after the instrument has been inserted, as described, until the blade is below the lower end of the cork, when a quarter-turn of the handle will bring the blade under the cork, which is then easily drawn by an upward pull.

I am aware of Patent No. 59,241, granted to Karl Loeffler, October 30, 1866, and disclaim the same as making any part of my invention.

What I claim as my invention is—

In a cork-extractor having a tapered stock and a segment-shaped lateral blade, the lateral blade *a*, having a convex lower edge bent outwardly, and the spur *b*, substantially as described, for the purpose set forth.

WILLIAM ENGELSDORFF.
